UNITED STATES PATENT OFFICE.

RUFUS HERRICK DORN, OF LOS ANGELES, CALIFORNIA.

MITER-BOX.

SPECIFICATION forming part of Letters Patent No. 769,307, dated September 6, 1904.

Application filed June 29, 1900. Serial No. 22,095. (No model.)

To all whom it may concern:

Be it known that I, RUFUS HERRICK DORN, a citizen of the United States, and a resident of the city of Los Angeles, in the county of Los Angeles, and in the State of California, have invented certain new and useful Improvements in Miter-Boxes, of which the following is a full, clear, and exact description or specification, reference being had to the annexed 10 sheet of drawings, and to the letters marked thereon.

My present invention consists of certain improvements in the miter-box for which Letters Patent have been allowed to me on the 2d 15 day of April, 1900, for which application for Letters Patent was filed on the 30th day of January, 1900, having the Serial No. 3,380 and issued to the applicant as Letters Patent No. 651,459, dated June 12, 1900.

20 My present improvements relate to the construction and operation of the retaining catch or catches whereby the angularly-movable backs of the miter-box (against which the moldings or other timber being cut in the miter-box rests while being cut) are adjusted and fastened at any required angles with the vertical plane of the saw, so as to get rid of a tendency to turn over or upset the miter-box by the user thereof placing his hands to 25 disengage the latch or catch, or either, back from the recess in the edge of the table, which I have found to occur with the retaining catch or catches shown in the drawings and described in the specification of my aforesaid-allowed 30 application for Letters Patent.

My present improvements also include a different construction of the circular attachments of the movable backs of the miter-box, by means of which circular attachments the 35 angular movements of the backs is obtained.

My present improvements include a deepening of the slot in the upper part of the saw-guide for the purposes hereinafter described.

My present improvements also include the 45 providing of pockets whereinto the stops for maintaining the molding or other piece of timber in position when being cut to an angular joint may be dropped to the level of the upper surface of the bottom or table of the miter-box 50 when it is required to have the upper surface

of the bottom or table of the miter-box free from any impediments which such stops in their operating positions produce.

On the annexed sheet of drawings, Figure 1 is a front elevation of my improved miter-box without the saw being shown therein and corresponding (with my present improvements added thereto) to Fig. 2 of the drawings of my aforesaid Letters Patent. Fig. 2 is an elevation of one of the angularly-movable backs of my miter-box in the position the reverse of that shown at Fig. 1 and showing the improved catch and operating-spring in elevation. Fig. 3 is an end elevation of the angularly-movable back of my improved miter-box, corresponding to Fig. 2. Fig. 4 is a plan of the back of my improved miter-box, corresponding to Figs. 2 and 3. Fig. 5 is an inverted plan of the under side of my improved miter-box, corresponding to Fig. 4 of the drawings forming part of my aforesaid application for Letters Patent, but showing my present improvements therein. Fig. 6 is a plan of my improved miter-box without showing the saw therein, the saw being in all respects identical with the saw shown in Fig. 1 of the drawings of my aforesaid Letters Patent and generally otherwise so well understood that it need not here be further referred to. Fig. 7 is a vertical sectional view of the whole miter-box, central and in front of the backs thereof, being taken on the line *c c*, Fig. 6. Fig. 8 is an enlarged detailed perspective view of a portion broken out of the table and showing the slot for the stop and a portion of the slot at the pocket broken out, so that the bottom of the pocket appears in section and shows the stop resting in the pocket.

In Fig. 1 the right-hand angularly-movable back of my improved miter-box is marked A, and the left-hand angularly-movable back of my improved miter-box is marked B. The retaining-catch levers are marked C and D, respectively, the larger part of which is seen only in dotted lines in Fig. 1, being situated at and pivotally fastened to the rear of the backs A and B. For the purpose of better showing the arrangement and construction of my improved catches for retaining the angularly-movable backs, the drawings are enlarged in Figs. 2, 3, 4, 5, 6, 7, and 8, so that the parts are not to scale.

- larly-movable backs A and B in their required positions I have included in the drawings the detached view of the right-hand back (marked A) and showing the rear thereof at Fig. 2. As 5 will be seen from Fig. 2, the retaining-catch consists of a lever C, whose upper end may project, as is there shown, slightly above the upper edge of the top of the back A, so as to be easily pushed by the hand of the user into 10 the position shown in dotted lines in Fig. 1 with respect to the retaining-catch lever D. The retaining-catch lever C is pivoted upon the pivoting screw or pin C', fastened into the back A. The spring E, fastened to the bottom 15 flange of the back A and bearing against the stop F, always presses against the upper part of the retaining-catch C, thereby maintaining the claw C'' of the retaining-catch engaged with any one of the recesses G in the 20 bottom of the edge of the table or bottom plate H of the miter-box, and when it is required to move the back A from any one angular position to another angular position the lever C is pressed inward into the position 25 shown with respect to the corresponding lever D in dotted lines in Fig. 1, whereby the catch C'' is disengaged from any one of the recesses G, thereby leaving the back A or the back B, as the case may be, free to be moved around 30 angularly upon the axis of the miter-box in the plane of the saw, and when the back A or the back B has been brought to the requisite angle the pressure of the workman's hand upon the lever C is released, when the spring 35 E forces it backward and causes the catch C'' to engage with any one of the recesses G or to grip tightly against the non-recessed parts of the circular bottom.
- With reference to Fig. 5 of the drawings, 40 the right-hand back A is fastened by screws a a to the ring I, and the back B is fastened to the ring J by the screws b b. The rings I and J are each respectively carried in circular recesses separated from each other in the 45 bottom of the miter-box, these recesses being formed by means of the two projecting circular beads or rings K K and L L, respectively, as shown at Fig. 5, while for the purpose of providing a more effective bearing for 50 the smaller ring J, to which the movable back B is fastened by the screws b b, the central projecting boss M is provided, the hole in the ring J J fitting thereto, while both rings I I and J J are retained in their places 55 in the bottom of the table H H of the miter-box by the plate N. (Indicated in dotted lines in Fig. 5.) The stops R are of the same construction as are the corresponding stops in the aforesaid Letters Patent and for the purpose 60 of allowing the said stops to be moved into the position whereat they will not project above the upper surface of the bottom plate or table H and at the same time preventing them from falling from the miter-box when 65 at the frontends of the segmental grooves O O,

in which they are movable. These ends of these grooves—that is to say, the ends thereof toward the front of the miter-box—are each provided with a pocket (shown dotted and marked P P in Fig. 5 and in elevation at Fig. 1) fastened at those ends of the segmental grooves O, so that the stops R R when moved to the front ends of the grooves O O may drop into the pockets and remain there ready to be lifted up out of either of the pockets P P when 70 again required to be fixed adjustably in the grooves O O. In order that a piece of timber wider than the half-diameter of the table H of the miter-box may be placed in or upon said miter-box for being cut to a right angle or to any 75 other angle, it is necessary that the front saw-guide (marked S, shown in Fig. 1) should be capable of being maintained at any required height above the top of the table H, so that a space may be left between its bottom edge and 80 the upper surface of the table H to admit such wider piece of timber into and to bear against the back of the miter-box while being cut to the angle required. For this purpose that part of the slot X in the front saw-guide S is 85 formed much deeper than is the corresponding slot shown in the drawings of my aforesaid allowed application for Letters Patent, so that the back of the saw may descend through this deepened part of the slot until the aforesaid 90 wider piece of timber is cut through. When the cutting edge of the saw has reached its lowest position, the lower edge of the saw-guide S remains resting upon such wider piece 95 of timber until such wider piece of timber, now cut, has been removed, when the saw-guide S drops to its lowest position, as it is shown in Fig. 1. For the purpose of insuring that the backs A and B shall always be in their 100 true operating position with each ring I and J, respectively, the backs A and B have a transverse projection Y at their bottom, which enters a corresponding slot in each ring, as shown.

Having now described the nature of my said 110 invention and the best system, mode, or manner I am at present acquainted with for carrying the same into practical effect, I desire to observe in conclusion that what I consider to be novel and original, and therefore claim 115 as the invention to be secured to me by Letters Patent, is as follows:

1. In a miter-box, the arrangement for carrying the two movable "backs" consisting of two rings each carried in a separate recess in the 120 under side of the bottom of the miter-box, to each of which rings one of the angularly-movable backs of the miter-box is attached by a rectangular projection at the bottom of each back entering a slot in the corresponding ring 125 and screws passing through both for holding each back to its corresponding ring, substantially as hereinbefore described.

2. The combination of the angularly-movable backs of a miter-box, the pivotally-carried 130

catches thereof, the upright levers of said catches, the springs operating said levers, the separate rings, one for each back with a slot therein for receiving the projection at the bottom of each back and to each of which one of the backs is connected by screws passing through the base of each back and into each ring, substantially as hereinbefore described.

5 3. The combination with the circular table of a miter-box having slots and stops of the pockets at the under side of the circular table whereto the stops are received when said stops are not in use, substantially as hereinbefore described.

10 4. In a miter-box the combination of the circular table, having slots and stops adjustable therein and enlargements of the slots and stops

through which such stops may pass, angularly-movable backs, the retaining-catches with upright operating-levers, the springs for operating the retaining-catches in and out of the recesses in the circular table, the rings to which the backs are fastened separated by a circular ring at the under side of the table and the pockets, substantially as hereinbefore described.

15 In testimony whereof I have hereunto set my hand and seal, this 23d day of May, 1900, in the presence of two subscribing witnesses.

RUFUS HERRICK DORN. [L. S.]
